J. P. SMITH.
JOINT FOR SECTIONAL FIRE SCREENS.
APPLICATION FILED JAN. 13, 1922.

1,413,364.

Patented Apr. 18, 1922.

UNITED STATES PATENT OFFICE.

JOHN P. SMITH, OF NEW HAVEN, CONNECTICUT, ASSIGNOR TO THE JOHN P. SMITH & CO., OF NEW HAVEN, CONNECTICUT, A CORPORATION.

JOINT FOR SECTIONAL FIRE SCREENS.

1,413,364.

Specification of Letters Patent. Patented Apr. 18, 1922.

Application filed January 13, 1922. Serial No. 528,893.

To all whom it may concern:

Be it known that I, JOHN P. SMITH, a citizen of the United States, residing at New Haven, in the county of New Haven and

5 State of Connecticut, have invented a new and useful Improvement in Joints for Sectional Fire Screens; and I do hereby declare the following, when taken in connection with the accompanying drawings and the 10 characters of reference marked thereon, to be a full, clear, and exact description of the same, and which said drawings constitute part of this application, and represent in—

Fig. 1 a view in front elevation of a three-panel, sectional fire-screen provided with my improved joint-unit.

Fig. 2 a plan view thereof, the end panels of the screen being shown as turned inwardly by broken lines.

20 Fig. 3 an enlarged, broken, sectional view of the screen through one of the joints thereof on the line 3—3 of Fig. 2.

Fig. 4 a broken, detached view in elevation, partly in section, of one of my improved joint-units, with the coupling-screws thereof removed.

Fig. 5 a view in transverse section on the line 5—5 of Fig. 4.

30 My invention relates to an improved joint-unit for folding, sectional fire-screens, the object being to provide a simple, convenient and effective joint-unit constructed with particular reference to permitting the individual panels of a folding sectional fire- 35 screen to be removed and replaced, as it may be desired, to increase or decrease the screen, without any riveting, cutting or filing operations, and so as to permit the joint-units to be re-used without change or repair.

40 With these ends in view, my invention consists in a joint-unit for sectional fire-screens, the said unit comprising a tie-rod, coupling-plates mounted in predetermined relative positions upon the ends thereof and 45 each provided, on opposite sides of the rod, with pivot-members, and removable pivots for one of the said plates.

50 My invention further consists in a joint-unit comprising a tie-rod, coupling-plates mounted in predetermined relative positions upon the ends thereof, fixed upstanding pivots located upon one of the said plates on opposite sides of the rod, and removable pivots for the other plate.

55 In carrying out my invention, as herein

shown, my improved joint-unit consists of a tie-rod 10 provided at its respective ends with elongated, round-ended coupling-plates 11 and 12 transversely-arranged with respect to it and parallel with respect to each other, these plates having fixed predetermined relative positions, whatever their form and special construction, which may change without departing from my invention. As shown, the upper plate 11 is provided on opposite sides of the rod 10 with corresponding threaded pivot-holes 13 for the reception of removable pivots, each consisting of a screw 14 and a knob 15, while the lower plate 12 is provided on opposite sides of the rod with permanently-applied, upstanding, rounded, stud-like pivots 16 respectively aligned with the threaded pivot-holes 13 of the upper plate. As herein shown, the ends of the rod 10 are formed with square rivets 17, which prevent the coupling-plates 11 and 13 from turning thereupon, whereby the alignment of the pivot-holes 13 and pivots 16 is at all times maintained. The tie-rod 13, plates 11 and 12, the removable pivots 14 having knobs 15, and the fixed pivots 16, together constitute one of my joint-units, of which the number employed in any one screen will depend upon the number of panels.

85 The panels of the sectional-screen may be of any approved construction, so long as they are provided at their ends with sockets or pivot-members for combination with my improved joint-units.

90 As herein shown, the screen consists of a wide center panel and two narrow panels. The center panel comprises a square of heavy wire-netting 18, horizontal upper and lower tubes 19 and vertical end tubes 20, which latter extend above and below the said upper and lower tubes. The end panels each consist of an oblong, rectangular section of heavy wire-netting 21, horizontal upper and lower tubes 22 and vertical end tubes 23. 95 With panels as thus constructed, the open ends of the end tubes 20 and 23 provide sockets for the removable pivots 14 of the joint units and for the fixed pivots 16 thereof.

100 In the use of my improved joint-unit, the open lower ends of the adjacent end tubes of two screen-panels are set over the respective fixed pivots 16 of the lower coupling-plate 12 of the joint-unit, after which the 110

open upper ends of the tubes are respectively aligned with the threaded pivot-holes 13 in the coupling-plate 11 of the joint-unit, to permit the passage downward through the 5 said holes into the upper ends of the tubes, of the removable pivots 14, which are screwed into place by their knobs 15. To remove the joint-unit as for taking out a panel or disassembling a screen, it is only 10 necessary to unscrew the removable pivots 14 by their knobs 15, after which the upper ends of the end tubes of the panels are spread apart and so cleared from the upper coupling-plate and thus permitted to have 15 their lower ends lifted off the fixed studs 16 upstanding from the lower coupling-plate 12.

It will thus be seen that I am enabled, by my improved sectional-screen joint-unit 20 to readily and without the use of tools, remove and insert the screen-panels as it may be desired to increase or decrease their number, whereas, heretofore, screen-joints have been riveted in place, so as to require filing 25 or cutting to remove them, after which they cannot be re-used, as under my invention. Furthermore, the user of a screen provided with my improved joint-units may order additional sections and joints and combine 30 them without having to send the screen to the factory or to call in a skilled mechanic.

I claim:

1. A joint-unit for folding, sectional fire-screens, comprising a tie-rod, coupling-plates 35 mounted in predetermined relative positions upon the ends thereof, and each provided on opposite sides of the rod with pivot-mem-

bers, the pivots for one of the said plates being removable.

2. A joint-unit for folding, sectional fire- 40 screens, comprising a tie-rod, coupling-plates mounted in predetermined relative positions upon the ends thereof, threaded pivot-openings located in one plate on opposite sides of the said rod, fixed pivots located upon the 45 other plate on opposite sides of the rod and aligned with the respective pivot-holes in the other plate, and removable pivots for the plate provided with pivot-holes.

3. In a folding, sectional fire-screen, the 50 combination with panels provided with end tubes open at their ends to form sockets, of a joint-unit comprising a tie-rod, coupling-plates mounted in predetermined relative positions upon the ends thereof, one of the said 55 plates being formed with two threaded pivot-holes located on opposite sides of the rod, and the other plate having two fixed pivots located on opposite sides of the rod and respectively aligned with the pivot-holes 60 in the other plate, and removable pivots for the plate having screw-holes, whereby adjacent open ends of the said tubes are set over the said studs, and whereby the opposite 65 open ends of the said tubes are aligned with the said pivot-holes for the reception of the said removable pivots.

In testimony whereof, I have signed this specification in the presence of two subscribing witnesses.

JOHN P. SMITH.
